COMBINED FOUR-CHANNEL TAPE PLAYER AND RECEIVER

Andrew Kainass, Syracuse, N.Y., assignor to
General Electric Company, Syracuse, N.Y.

Filed Apr. 7, 1972, Ser. No. 242,296

Term of patent 14 years

Int. Cl. D14—03

U.S. Cl. D26—14 B

FIG.1.

FIG.2.

FIG.3.

FIG.4.

FIG.5.

FIG.6.

FIG. 1 is a front elevation view of a combined four-channel tape player and receiver in accordance with my design;

FIG. 2 is a top plan view;

FIG. 3 is a right side elevation view;

FIG. 4 is a left side elevation view;

FIG. 5 is a bottom plan view; and

FIG. 6 is a rear elevation view.

I claim:

The ornamental design for a combined four-channel tape player and receiver, as shown.
